(57) **CLAIM**

The ornamental design for a light tactical vehicle hull, as shown and described.

DESCRIPTION

The invention described here may be made, used and licensed by and for the U.S. government for governmental purposes without paying royalty to us.

FIG. 1 is a front, left, top isometric view of a light tactical vehicle hull;

FIG. 2 is a second, close-up, front, left, top isometric view thereof;

FIG. 3 is third, close-up, front, left, top isometric view thereof;

FIG. 4 is a rear, left, top isometric view thereof;

FIG. 5 is a left side view thereof;

FIG. 6 is a right side view thereof;

FIG. 7 is a front view thereof;

FIG. 8 is a rear view thereof;

FIG. 9 is a top plan view thereof;

FIG. 10 is a bottom plan view thereof;

FIG. 11 is a bottom, front, left isometric view thereof;

FIG. 12 is a bottom, front, right isometric view thereof;

FIG. 13 is a bottom, rear, left isometric view thereof;

FIG. 14 is a second bottom, rear, left isometric view thereof;

FIG. 15 is a bottom, rear, right isometric view thereof; and,

FIG. 16 is a sectional view taken at line 16-16 on FIG. 9.

All views are orthogonal unless otherwise indicated. The broken lines shown on FIG. 1 depict environmental structure only, and form no part of the claimed design.

1 Claim, 16 Drawing Sheets
